[57] CLAIM

The ornamental design for a combined golf ball teeing and retrieving device, as shown and described.

DESCRIPTION

FIG. 1 is a side elevation of a combined golf ball teeing and retrieving device showing my new design.

FIG. 2 is a plan view of my new design as seen from one end.

FIG. 3 is a plan view of my new design as seen from the opposite end to that shown in FIG. 2.

FIG. 4 is a perspective view of my new design as seen from a point above and to the right of one end.

FIG. 5 is a perspective view of my new design as seen from a point above and to the left of the opposite end. The handle is shown fragmentarily to indicate indeterminate length and the broken lines of a ball and tee are for illustrative purposes only.
